CLAIM

We claim, the ornamental design for a luminaire, as shown and described.

DESCRIPTION

FIG. 1 is a first side plan view of the invention, the luminaire being symmetric about a center axis;

FIG. 2 is a top plan view of the embodiment of FIG. 1; FIG. 3 is a bottom plan view of the embodiment of FIG. 1; and,

FIG. 4 is a first perspective view of the embodiment of FIG. 1. The degree of transparency or opaqueness of the lens of the luminaire forms no part of the claimed design. The lens of the claimed luminaire may have facets, lenslets or other treatments.

The dotted lines shown in FIGS. 1, 2 and 4 indicate that the outer diameter and shape of the lens may have any size diameter or curvature.

The dash-dot lines shown in FIGS. 1-4 are environmental and not part of the claimed design.

The dash-dot-dot lines shown between the heat sink portion and base portion in FIGS. 1, 3, and 4 indicate that the heat sink portion may be of any length.

The phantom lines shown in FIGS. 1, 3 and 4 are environmental and not part of the claimed design.

The color and shading of the luminaire forms no part of the claimed design, the luminaire according to the claimed design may be any color or combination of colors.

The surface treatment of the luminaire forms no part of the claimed design, the luminaire of the claimed design may have any surface treatment.

References to "side", "top", and "bottom" in the figure descriptions are not meant to require certain in-use orientation; a luminaire according to the claimed design may be used in any orientation.
